No. 653,548.

Patented July 10, 1900.

J. T. DEDMAN.

HAME TUG.

(Application filed Jan. 24, 1900.)

(No Model.)

Fig. 1

UNITED STATES PATENT OFFICE.

JAMES T. DEDMAN, OF SULLIVAN, ILLINOIS.

HAME-TUG.

SPECIFICATION forming part of Letters Patent No. 653,548, dated July 10, 1900.

Application filed January 24, 1900. Serial No. 2,605. (No model.)

To all whom it may concern:

Be it known that I, JAMES T. DEDMAN, a citizen of the United States, residing at Sullivan, in the county of Moultrie and State of Illinois, have invented a new and Improved Coupling for Harness, of which the following is a full, clear, and exact description.

One object of the invention is to so construct the coupling for a trace and hame-tug that much less leather is required in the construction of the tug and the sections may be rendered adjustable and may be locked in an adjusted position expeditiously, securely, and conveniently by means of a very simple, easily operated, and durable attachment.

A further object of the invention is to provide a coupling for a trace and hame-tug which will tend to strengthen the parts and dispense with the necessity of loops.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of a portion of a hame-tug and trace having the improvement applied, the two parts being shown as locked together. Fig. 2 is a horizontal section through the hame-tug and trace and the locking device as illustrated in Fig. 1. Fig. 3 is a transverse section taken substantially on the line 3-3 of Fig. 2, and Fig. 4 is a similar section taken practically on the line 4-4 of Fig. 2.

A represents the trace, B the hame-tug, and C the usual buckle employed in connection with said parts. The hame-tug B is provided with a number of apertures 10, extending through from one face to the other, as shown in Fig. 2. A band 11 is mounted to slide on the said hame-tug, and the said band is provided with ears 12, which ears are inclined in opposite directions where they connect with the body of the band, as shown in Fig. 1. A cam 13 is pivoted between the ears or lugs 12 of the band 11 by means of a pin 14 or the equivalent thereof, and a lever D is connected with the said cam, the handle portion of which lever at its free end is pro-

vided with a curved finger-section 16. A keeper E is attached to the trace A by means of a suitable shank 15, as shown in Fig. 2, and the said keeper is reduced in depth at its free end, thereby forming a shoulder 18, and the sides 17 of the end section of the reduced portion of the keeper are inclined in direction of the longitudinal center of said keeper, as shown in Fig. 1, so that the lugs or ears 12 of the band 11 may slide conveniently over the reduced portion of the keeper and engage with the shoulder 18, which shoulder limits the movement of the band 11 on the keeper.

A semicircular recess 19 is made in the front face of the reduced portion of the keeper E, at one side of the shoulder 18, and a recess 20 is made in the same face of the enlarged portion of the keeper, the recess 20 being longitudinally produced therein and is provided at the end farthest removed from the shoulder 18 with a depression 21, as shown in Fig. 2. Pins or spurs 22 are formed upon the inner face of the keeper, and these pins or spurs 22 are adapted to enter the apertures 10 in the hame-tug B.

In operation when the lever D is thrown in the direction of the hame-tug B, as shown in Fig. 2, the strap 11 may be removed from the keeper and slid along the hame-tug B, permitting the sections to be readily disconnected. When the two sections A and B of the harness are brought together, the pins 22 of the keeper are placed in suitably-located apertures 10 in the hame-tug B. Next the band 11 is slid over upon the reduced portion of the keeper to an engagement with the shoulder 18, and the lever D is then carried over in direction of the trace A, the cam 13 being at that time made to enter the recess 19 in the keeper, while the handle portion of the lever enters the recess 20, and the curved extremity of the handle-section of the lever enters the depression 21 in the said keeper. Thus the lever firmly locks the two sections A and B of the harness together, and yet the lever D may be readily grasped by the fingers to release the strap 11 from binding engagement with the keeper owing to the curved section 16 of the said handle.

It is obvious that the two parts A and B of the harness may be readily adjusted and

locked in adjusted position in the coldest of weather and while the operator is wearing gloves and that the expense of manufacturing the coupling is greatly reduced, since 5 there is no need of any loops to effect a locking engagement between the trace and hame-tug.

Having thus described my invention, I claim as new and desire to secure by Letters

10 Patent—

15 1. In a harness, a hame-tug and trace, a keeper secured to the trace, provided with pins adapted to enter apertures in the hame-tug, the said keeper being provided with a shoulder at a point between its ends, a semi-circular recess at one side of the shoulder and an elongated recess at the other side of the shoulder, a slide mounted to travel upon the hame-tug and upon the said keeper to an engagement with the shoulder thereof, and a lever carried by the said slide, the handle whereof is adapted to enter the elongated recess of the keeper, the said lever having a cam-section arranged to enter the semicircular recess in 25 the keeper, as and for the purpose specified.

20 2. In a harness, the combination, with a trace and hame-tug, the hame-tug being provided with apertures, a keeper secured to the trace and adapted to extend over the hame-tug, the keeper being provided with pins capable of entering the apertures in the hame-tug, the said keeper having a reduced portion whose sides are inclined, a shoulder at the termination of the inclined portions of the 35 sides, an elongated recess at one side of the said shoulder, and a semicircular recess at the opposing side of the shoulder, of a band held to slide upon the hame-tug, the said band having lugs inclined correspondingly to the inclining 40 nation of the sides of the reduced portion of the keeper and adapted for engagement there-

with, the lugs being also arranged to extend beyond the front face of the reduced portion of said keeper, and a lever provided with a cam-section, pivoted between the said lugs 45 and arranged to enter the concaved recess in the keeper, and a handle-section adapted to enter the elongated recess in the keeper, for the purpose specified.

3. In a harness, a hame-tug provided with 50 apertures, a trace provided with a keeper projecting from its end, said keeper being provided with a longitudinal recess in one face and on its other face with pins or spurs to enter the openings of the tug, a slide independent of the tug and keeper and fitted to slide thereon, and a cam-lever carried by the slide and engaging the keeper for locking the slide in position and the keeper to the tug, the handle portion of the cam-lever lying in the recess of the keeper when the parts are locked together, substantially as described.

4. In a harness, a hame-tug provided with 55 apertures, a trace provided with a keeper having a longitudinal recess and a semicircular recess in one face and provided with spurs or pins projecting from the other face and entering the apertures of the tug, a slide independent of the tug and keeper and fitted to slide thereon, and a cam-lever pivoted to the 60 slide and adapted to enter the semicircular recess of the keeper with its handle portion lying parallel with the keeper in the longitudinal recess thereof, substantially as described.

In testimony whereof I have signed my name to this specification in the presence of two subscribing witnesses.

75 JAMES T. DEDMAN.
